UNITED STATES PATENT OFFICE.

MORRIS B. OKUN, OF CHICAGO, ILLINOIS.

BED-RAIL ATTACHMENT.

1,076,833.

Specification of Letters Patent.

Patented Oct. 28, 1913.

Application filed January 13, 1913. Serial No. 741,674.

To all whom it may concern:

Be it known that I, MORRIS B. OKUN, a citizen of the United States, residing at Chicago, in the county of Cook and State of Illinois, have invented certain new and useful Improvements in Bed-Rail Attachments, of which the following is a specification.

This invention relates to improved means of attachment between the side rails and corner posts of metal beds and has for its principal object the provision of a bed rail attachment which shall be secure, neat, easily connected and disconnected, and in which the parts shall mutually support each other under the strains incident to use.

A further object of the invention is the standardization of parts whereby they are adapted to interchangeable use with rails of different size and posts of all degrees of curvature from an inch in diameter to those of square cross section.

This invention may be considered as in some respects an improvement upon the construction forming the subject matter of my Patent No. 1,001,882, dated August 29, 1911, the present construction being superior to the former in many respects which will be apparent as the description of the same proceeds.

In order that the invention may be readily understood by persons working in this art I have herein shown and described the same in connection with a preferred form of construction. However, as the invention is manifestly capable of embodiment in other and varied forms of construction the drawing and description are to be taken as illustrative and not in an unnecessarily limiting sense.

In the drawings: Figure 1 is a fragmentary view in perspective of a bed corner illustrating the improved form of bed rail attachment; Fig. 2 is a view similar to Fig. 1 with the bed rail detached; Fig. 3 is a vertical section on the line 3—3 of Fig. 4 through a bed rail and corner post at the point of attachment; Fig. 4 is a horizontal section on the line 4—4 of Fig. 3; Fig. 5 is a perspective view showing the end of the bed rail; Fig. 6 is a similar view of the attachment plate disconnected from the rail; and Fig. 7 is a similar detail of the pin retaining strip.

Referring to the drawings the portion of the bed end shown comprises a corner post designated by the reference numeral 11, a

cross bar 12 and the vertical end bars 13 connected together in the usual manner.

In Figs. 1 and 2 the corner posts are shown as round, while in Figs. 3 and 4 the post is shown as square and is designated by the reference numeral 11^a, the invention being applicable equally well to corner posts of round or square cross section and of any size without change in the form or size of the parts serving to attach the side rail and post.

To each of the corner posts of the bed is permanently attached a box-like bracket 14, clearly shown in Fig. 2. This bracket is formed from a blank of sheet metal which is so shaped and bent as to provide an externally concave end wall 15 having upwardly and downwardly projecting tongues 16 and 17 respectively which are then angularly bent to the horizontal position indicated in Fig. 2, these tongues being provided with apertures 18 and 19. The metal extends in spaced parallel relation from the end wall 15 in side walls 20 and 21. The side wall 20 has an upwardly extending tongue 22 which is likewise bent at right angles and serves as a point of attachment for the cross rail 23 by means of the rivet or rivets 24. The terminal portion of the material is angularly bent as indicated at 25, to abut against the opposed side wall 21, while the terminal portion of the material forming the side wall 21 is likewise bent angularly as indicated at 26, to overlap the terminal portion 25 to which it is secured by the rivet or rivets 27. The side wall 21 is provided with a vertically disposed slot 28 open above and the vertical edges of which occupy a position in substantially parallel relation to each other. It will thus be seen that the box brackets 14 upon opposite sides of the bed are rigidly connected together by the cross rail 23 and are provided with tongues 16 and 17 by means of which they are attached to the respective corner posts.

The corner post is provided with a pair of horizontally disposed slots 29 and 30 which are adapted to snugly receive the apertured tongues 16 and 17 and to permit the end wall 15 of the bracket to bear snugly against the exterior face of the corner post. To attain a close bearing contact of the bracket with the exterior wall of posts varying in curvature from a round post of small diameter as indicated in Figs. 1 and 2, to a

square post of any size, as indicated in Figs. 3 and 4, and including round posts of larger diameter, the curvature of the concave end wall 15 is such as to conform to the curvature of a post of small size so that when applied to round posts of larger size or to square posts the bearing contact will be along the vertical lines of the corners of the box bracket as indicated at 31 and 32 in Fig. 4 whereby the bracket will have a firm bearing in every case.

The apertures 18 and 19 are of dissimilar size so as to accommodate the two end portions of a wedge pin 33. In the form of construction illustrated the aperture 19 is shown as of larger size to adapt the pin to be inserted from below. The size and inclination of the wedge pin 33 is such as when driven home to draw the bracket firmly against the exterior wall of the post by means of the tongues 16 and 17. Prior to the insertion of the pin a retaining strip 34 of thin malleable metal, a strip of tin being suitable, and having a transversely disposed slot 35 is slipped over the tongue 17 and lies between the aperture 19 and the inner wall of the post. After the pin is inserted and driven home the lower end of the strip 34 is bent as indicated at 35, across and beneath the head of the pin and serves effectually to prevent its accidental dislodgement.

The construction thus far described serves to equip the corner posts of each bed end with a pair of box brackets immovably attached to the corner posts and also transversely connected to each other by means of the cross rail 23, these brackets forming a substantially integral part of the bed ends and serving in connection with the attachments carried by the side rails as a means for detachably connecting the side rails to the bed ends.

The side rails 36 are shown as of the usual angular construction having a horizontal portion 37 and a vertical portion 38. At each end of the side rail is firmly attached by means of the rivets 39, 40, an attachment plate 41 corresponding in size and outline to the interior of the outer side wall 21 of the box bracket. The lower portion of the plate is cut away to provide the vertically disposed downwardly opening notch 42 and in vertical alinement therewith the metal of the plate is laterally offset, as clearly shown at 43 in Fig. 6, for a distance corresponding to the thickness of the side wall 21, the width of the offset portion corresponding to the width of the slot 28 so that the said offset portion 43 will enter from above and snugly fit within the slot 28. The attachment between the plate 41 and the vertical portion 38 of the side rail is by means of the offset 43, the apertures 44, 45 in the latter being provided for

the accommodation of the rivets 39 and 40. The vertical extent of the offset 43 corresponds to the length of the slot 28.

In assembling the bed the end of the side rail is brought into position with the horizontal portion 37 overlying the box bracket 14 and dropped vertically into position so that the plate 41 will enter the said bracket, the offset 43 entering the slot 28 and the outer side wall 21 of the bracket occupying a position, as indicated in Fig. 4, between the plate 41 and the vertical portion 38 of the side rail. As shown in Fig. 3, the edges of the plate 41 will bear snugly against the end walls of the bracket and the shoulders of the offset will likewise bear snugly against the side walls of the slot 28 while the lower edge of the offset will rest against the bottom wall of the slot 28. The plate 41 being rigidly attached to the rail, the rail itself will thus be supported along five lines of contact with the bracket and also by abutment of the end of the rail against the corner post whereby any angular movement of the parts is effectually prevented.

I claim:

1. In a bed rail attachment, the combination with the corner post, of a box bracket having side and end walls, one of the end walls having upper and lower apertured tongues extending horizontally into the posts, a pin disposed within the apertures and bearing against the inner wall of the post, means engaging the pin to prevent accidental withdrawal, and means to detachably connect the side rail to the bracket, substantially as described.

2. In a bed rail attachment, the combination with the corner post, of a box bracket having side and end walls, one of the side walls having a vertically disposed upwardly opening notch, and one of the end walls having upper and lower apertured tongues extending horizontally into the posts, a pin disposed within the apertures and bearing against the inner wall of the post, means to engage beneath the pin to prevent accidental withdrawal, and means carried by the rail and adapted to engage within the notch to detachably connect the rail and bracket, substantially as described.

3. In a bed rail attachment, the combination with the corner post, of a box bracket having side and end walls, one of the side walls having a vertically disposed upwardly opening notch, and one of the end walls having upper and lower apertured tongues extending horizontally into the posts, a pin disposed within the apertures and bearing against the inner wall of the post, means to engage the pin to prevent accidental withdrawal, and means to detachably connect the rail to the bracket, said means comprising a plate corresponding in size to the interior side wall of the bracket and having

an integral offset portion adapted to fit within the slot of such side wall, the extent of the offset from the plane of the plate corresponding substantially to the thickness 5 of the bracket wall so as to accommodate the said wall between the plate and rail, and fastening means connecting the offset portion and the rail, substantially as described.

4. In a bed rail attachment, the combination with the corner post, of a box bracket having side and end walls, one of the side walls having a vertically disposed upwardly opening notch, and one of the end walls having upper and lower apertured tongues 10 extending horizontally into the posts, a wedge pin disposed from below within the apertures of the tongues and bearing against the inner wall of the posts, means to engage beneath the head of the pin to prevent accidental withdrawal, and means 15 to detachably connect the rail to the bracket, said means comprising a plate corresponding in size to the interior side wall of the bracket and having an integral offset portion adapted to fit within the slot of such side wall, the extent of the offset from the plane of the plate corresponding substantially to the thickness of the bracket wall so as to accommodate the said wall between 20 the plate and rail, and fastening means connecting the offset portion and the rail, substantially as described.

5. In a bed rail attachment, the combination with the corner post, of a box bracket having side and end walls, one of the side walls having a vertically disposed upwardly opening notch, and one of the end walls having upper and lower apertured tongues 25 extending horizontally into the posts, a wedge pin disposed from below within the apertures of the tongues and bearing against the inner wall of the posts, means to engage beneath the head of the pin to prevent accidental withdrawal, and means to 30 detachably connect the rail to the bracket, said means comprising a plate corresponding in size to the interior side wall of the bracket and having an integral offset portion adapted to fit within the slot of such side wall, the extent of the offset from the plane of the plate corresponding substantially to the thickness of the bracket wall so as to accommodate the said wall between 35 the plate and rail, and fastening means connecting the offset portion and the rail, substantially as described.

horizontal rail portion overlying the bracket and the vertical rail portion lying alongside the bracket and covering the slot, substantially as described.

6. In a bed rail attachment, the combination with the corner post, of a box bracket comprising material bent to form an outwardly concave outer end wall, parallel side walls, and then overlapped to form an inner end wall, apertured tongues projecting upwardly and downwardly from the outer end wall adapted to be angularly bent so as to project horizontally into the post, the inner side wall provided with a tongue extending upwardly and adapted to be bent horizontally for attachment to the cross rail of the bed, a pin disposed within the apertures and bearing against the inner wall of the post, means to engage the pin to prevent accidental withdrawal, and means to 65 detachably connect the side rail to the bracket, substantially as described.

7. In a bed rail attachment, the combination with the corner post, of a box bracket comprising material bent to form an outwardly concave outer end wall, parallel side walls, and then overlapping to form an inner end wall, apertured tongues projecting upwardly and downwardly from the outer end wall adapted to be angularly bent so as to project horizontally into the post, the inner side wall provided with a tongue extending upwardly and adapted to be bent horizontally for attachment to the cross rail of the bed, the outer side wall provided with 80 an upwardly opening notch having substantially parallel side walls, a wedge pin disposed from below within the apertures of the tongues and bearing against the inner wall of the post, means to engage beneath 85 the head of the pin to prevent accidental withdrawal, a plate conforming in shape and size to the side wall of the bracket and having a portion offset for a distance corresponding substantially to the thickness of 90 the bracket wall and of a width adapted to fit snugly within the slot, and means to rigidly connect the offset portion of the plate to the side rail, substantially as described.
